UNITED STATES PATENT OFFICE.

CARL GÖPEL, OF HALLE-ON-THE-SAALE, GERMANY.

DEVICE FOR DISPOWDERING CONFECTIONERY.

Application filed January 21, 1927, Serial No. 162,612, and in Germany January 28, 1926.

The filled in cores of pralines and similar confectionery, are, after leaving the mould box, subjected on an endless travelling sieve to the action of air-blasts for the removal of adhering mould powder before they are finally coated.

The present invention relates to a dispowdering device of this kind and consists in the provision of brushes arranged opposite the air-blasts so as to support the thin-walled articles without exposing them to injury and at the same time to enhance the dispowdering process by diverting the air current around the articles.

Fig. 1 of the accompanying drawings represents a longitudinal section of the device, and

Fig. 2, a cross-section of the same.

The dispowdering compartment *b* contains an endless sifting apron *a* which extends right through the compartment and which receives the pralines as they are scooped out of the mould box. A set of air-nozzles *c* is arranged under apron *a*, and another set *d* is arranged above the same so that both sides of the pralines will be exposed to an air-blast for the removal of the adhering powder. To support the pralines, in one instance direct and in the other instance through the medium of the apron, against the air-blasts, resilient elements, preferably brushes *f* and *g*, are arranged opposite the air-nozzles. The brush *f* which supports the pralines direct, consists of an endless travelling brush band which follows the movement of the apron *a*. The brush *g* may be a stationary one. These

brushes, while providing a soft support for the pralines, also deflect the air-current and divert them around the articles so that an effective cleaning of the same takes place before they are passed on to the coating device.

The adhering mould powder is either collected in a tray *h* at the bottom of the chamber *b* or removed by means of an exhauster *i*. A fan *e* supplies the air to the nozzles *c* and *d*.

I claim:

1. A device of the character described for dispowdering pralines and the like comprising an endless travelling sifting apron for carrying the articles, air-blasts arranged so as to play on said apron from opposite sides of the same, and a resilient support for the articles arranged opposite each air-blast.

2. A device of the character described for dispowdering pralines and the like comprising an endless travelling sifting apron for carrying the articles, air-blasts arranged so as to play on said apron from opposite sides thereof, and a brush arranged opposite each air-blast as support for the articles.

3. A device of the character described for dispowdering pralines and the like comprising an endless travelling sifting apron for carrying the articles, air-blasts arranged so as to play on said apron from opposite sides thereof and in different positions, and brushes arranged opposite the air-blasts as supports for the articles, the brush at the top side of the apron being composed of an endless brush band.

CARL GÖPEL.
